CLAIM

The ornamental design for a combined module and pad, as shown and described.

DESCRIPTION

FIG. 1 is a top perspective view of a combined module and pad;

FIG. 2 is a right side view thereof;

FIG. 3 is a left side view thereof;

FIG. 4 is a back elevation view thereof;

FIG. 5 is a front elevation view thereof;

FIG. 6 is a top, plan view thereof;

FIG. 7 is a bottom, plan view thereof; and,

FIG. 8 is a bottom perspective view thereof.

The short, broken lines shown in the figures illustrate portions of the combined module and pad that form no part of the claimed design. The dash-dot lines shown in the figures illustrate the bounds of the claim that form no part of the claimed design.

1 Claim, 6 Drawing Sheets
